UNITED STATES PATENT OFFICE.

PETE DUNFORD, OF SUMMIT, GEORGIA.

COTTON-PRESS.

No. 806,245.

Specification of Letters Patent.

Patented Dec. 5, 1905.

Application filed May 22, 1905. Serial No. 261,645.

To all whom it may concern:

Be it known that I, PETE DUNFORD, a citizen of the United States, residing at Summit, in the county of Emanuel and State of Georgia, have invented a new and useful Cotton-Press, of which the following is a specification.

This invention relates to pressers for forming material into bales, and while capable of general application is designed more especially for the formation of cotton bales.

One object of the invention is to provide a novel form of press-box in conjunction with a pair of oppositely-movable plungers, one of which moves to effect initial compression of the material in the baling-chamber and then becomes locked to form a head-block for resisting the movement of the material during the operation of the second or main compression-plunger.

A further object of the invention is to provide means for readily controlling the operation of the plunger and to so arrange the gearing connections of the same that during the compressing operation the movement will be slow and powerful and in returning to normal position the movement will be rapid, so that the parts may be quickly adjusted to initial position in readiness to permit the introduction of the material to form another bale.

A still further object of the invention is to provide improved means for discharging the bale after the completion of the operation.

With these and other objects in view, as will more fully hereinafter appear, the invention consists in certain novel features of construction and arrangement of parts herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a vertical section of a baling-press constructed in accordance with the invention. Fig. 2 is a plan view of the same, parts being broken away in order to more clearly illustrate the construction. Fig. 3 is a sectional plan view of the press on the line 3 3 of Fig. 1. Fig. 4 is a similar view on the line 4 4 of Fig. 1.

Similar numerals of reference are employed to indicate corresponding parts

throughout the several figures of the drawings.

The various working parts of the press are mounted in a strong frame, including sill members 10 and vertical posts 11, the latter being rigidly connected at the top by beams 12 and near the bottom by beams 13, while auxiliary transverse beams 14 are arranged at the opposite ends of the press at a point 65 some distance below the top of the frame.

The baling-chamber is formed in sections, and the bottom of said chamber comprises a plunger 15, which is moved from the full-line position shown in Fig. 1 to the dotted-line 70 position shown in the same figure during the final compressing operation. The side walls 16 of the lower portion of the baling-chamber are rigidly connected to the frame and the side walls 17 of the upper portion of said 75 chamber are also rigidly secured to said frame.

At the top of the chamber are arranged inclined hopper members 18 to facilitate the introduction of the material to be compressed. The intermediate portion of the 80 baling-chamber is formed of two side and two end walls, all of which are of the same construction and each of which may be removed independent of the others. Each of these walls 20 comprises a pair of horizontally-disposed parallel bars 21, the end portions of which are reduced in thickness and bear against the inner faces of the vertical posts 11, said posts being preferably rounded at the points where they engage with the 85 bars 21. These bars are connected by metal plates 22, which are rigidly bolted to the bars and are spaced from each other, as shown in Figs. 1 and 4, to permit the introduction of the bands or ties which are placed around the bale to hold the same compressed. The reduced end portions of the bars 21 are so arranged that if one of the side members of the 90 press-box is moved endwise its bars may be removed from engagement with the vertical 95 posts at one end and then by movement in the opposite direction the opposite ends of the bars 21 may be cleared, so that the whole of the side wall may be detached, leaving the baling-chamber open for the removal of the 100 compressed bale, and, if necessary, all of these side walls may be removed to accomplish the desired result.

To the central portion of the plunger is secured a double rack-bar 26, the upper end of which is secured to a frame 27, and the frame, which preferably is in the form of diagonally-disposed bracing 110

members, is rigidly secured to the corners of the plunger in order to form a rigid structure and prevent yielding of any part of the plunger during the compression operation.

5 The upper frame 12 is provided with bearings for the support of a pair of parallel shafts 29 and 30, carrying gears 29' and 30', that intermesh with rack 26. The shafts also carry friction-wheels 31 and 32, respectively, 10 these wheels being of different diameter and being alternately engaged by a friction-wheel 33, the larger wheel 32 being driven during the compression-stroke of the plunger and the smaller wheel 31 being driven during 15 the return of the plunger to its initial position.

The friction-wheel 33 is mounted on a shaft 34, the outer portion of which is held in a pivotally-mounted bearing 35, and on the outer end of the shaft are fast and loose pulleys 37 20 38, a suitable belt and belt-shifting mechanism being employed and connected in the usual manner. The inner portion of the shaft 33 passes through a bearing formed in a slidably-mounted block 39, to which is secured a slide-bar 40, and the outer end of the bar is connected to an operating-lever 41, which may be locked in any suitable position 25 by a notched rack 42 and a latch or other locking device carried by the lever. When moved to one position, the shaft 34 will be 30 slightly shifted to permit the friction-wheel 33 to engage the friction-wheel 32, and if moved to the opposite position the friction-wheel 33 will be engaged with the friction-wheel 31.

At the opposite ends of the plunger 25 are arranged spring-pressed bolts 42, that preferably are provided with inclined end portions, so that when the plunger is depressed 40 past the transverse beams 14 the spring-bolts will be driven inward and will then be thrust outward to the position shown by dotted lines in Fig. 1, thus automatically locking the upper plunger from upward movement, and 45 said upper plunger thus forms a fixed head-block during the remainder of the compressing operation. The upper plunger is provided with bearings for the reception of a transversely-disposed shaft 44, that is connected to the several bolts 42 and is provided with an operating-lever 45 to withdraw all of the bolts simultaneously and permit the upward movement of the head-block after 50 the formation of each bale.

55 The lower bracing-frame 13 is provided with bearings for the support of a pair of shafts 50 and 51, that carry friction-wheels 52 and 53, respectively, and with these may engage a friction-wheel 54, carried by a shaft 60.

55. The shafts 50 and 51 are further provided with intermeshing gears 56 of uniform diameter, and said gears intermesh with vertical racks 57, formed on a U-shaped frame 58, that is adapted to suitable guideways 59, 65 and at its upper end is connected to the lower

plunger 15. The outer portion of the shaft 55 extends through a bearing-block 60, and the inner portion of said shaft is carried by a slidably-mounted bearing 62, that is carried by a bar 63, extending through suitable guiding-openings and provided at its outer end with a handle 64, which when moved in one direction or the other will shift the position of the shaft and cause the friction-wheel 54 to engage either the friction-wheel 52 or the 75 friction-wheel 53. The bar is held from movement by a pair of pawls 65, that are pivoted to the bar and engage with the teeth of a double rack 66, secured to the bed-plate of the machine or to the floor adjacent to the 80 machine.

The friction-wheel 53 is of much less diameter than the friction-wheel 52 and is engaged by the friction-wheel 54 when the plunger is to be lowered after the formation of a bale. 85 During the formation of a bale the friction-wheel 54 is kept in engagement with the friction-wheel 52, so that a slower and more powerful movement is secured. The outer end of shaft 55 carries fast and loose pulleys 67 90 and 68, to which a suitable belt is applied.

In the operation of the device the parts are normally in the position shown in Fig. 1, and the material to be compressed is fed from the gin into the baling-chamber. After the 95 baling-chamber is partly filled with loose cotton the lever 41 is operated for the purpose of engaging the friction-wheel 33 with the friction-wheel 32, and the plunger is driven down part of the way, slightly compressing 100 the cotton, and may then be raised in order to permit the introduction of a fresh quantity, and this operation may be repeated a number of times until at the final movement of the upper plunger 25 said plunger is forced 105 down until the bolts 42 engage under the transverse bars 14 and the plunger is then rigidly locked in place and forms a fixed head-block. The handle 64 is then manipulated to throw the friction-wheel 54 into engagement with the friction-wheel 52, and the lower plunger 15 is forced up in order to effect the 110 final compression of the bale, after which the tying may be accomplished in the usual manner. The side walls 20 or any number of 115 them may be removed, and after the upper plunger is retracted the lower plunger serves as a support for the bale, and the latter may be slid out from the side or from the end of the baling-chamber, after which the side walls 120 are replaced and the lower plunger is lowered in readiness for a second operation.

Having thus described the invention, what is claimed is—

1. In a baling-press, a press-box having 125 detachable side walls each formed of a plurality of spaced bars, and spaced plates extending across and securing the bars together, the bars being removably held in place by the frame of the press. 130

2. In a baling-press, the combination with a plunger, of a double rack connected thereto, a pair of gears intermeshing with the rack, shafts carrying the gears, friction-disks of 5 different diameter, respectively, arranged on the shafts, a driving friction-wheel movable into engagement with either of the shaft-carried wheels, and means for adjusting the position of the driving-wheel.

10 3. The combination with a plunger, of a double rack connected thereto, a pair of gears intermeshing with the racks, shafts carrying the gears, friction-wheels mounted on the shafts, and of different diameters, respectively, a driving-shaft mounted in pivoted bearings, a friction driving-gear mounted on the shaft, and means for adjusting said shaft to place the driving-wheel in engagement with either of the first friction-wheels.

15 4. The combination in a baling-press, of a

plunger, a double rack-bar connected thereto, a pair of gears intermeshing with the rack-bar and with each other, shafts carrying said gears, friction-wheels mounted on the shafts and of different diameter, respectively, adjustable journal-boxes, a shaft carried thereby, a friction-wheel mounted on the shaft and arranged between the first friction-wheels, a slide-bar connected to one of the journal-boxes, pawls carried by the slide-bar, and racks for engaging said pawls and locking the same from movement.

20 In testimony that I claim the foregoing as my own I have hereto affixed my signature in the presence of two witnesses.

PETE DUNFORD.
